ATTORNEY

UNITED STATES PATENT OFFICE.

JEAN R. KRAUSE, OF NEW YORK, N. Y.

DESIGN FOR A HAIR-ORNAMENT.

SPECIFICATION forming part of Design No. 12,913, dated May 2, 1882.

Application filed March 7, 1882. Term of patent 7 years.

To all whom it may concern:

Be it known that I, JEAN R. KRAUSE, of the city, county, and State of New York, have invented a new and original Design for Hair-Ornaments, of which the following is a full, clear, and exact description, reference being had to the accompanying drawing, making part of this specification.

The design consists of a series of scallops, which are united at their butt-ends and made to spread from said butt-ends to their tips in the form of a fan, with curved sides and rounded points.

The drawing represents a plan of my hair-ornament.

In this drawing, the letter A represents the head, from which extends a series of scallops, B B' B² B³ B⁴ B⁵. The butt-ends of these scallops are close together, and they are fastened 20 in the head A. From their butt-ends they

spread open, and their tips are rounded off, as shown, their sides being connected by curved hairs. The outer sides of the extreme scallops B B⁵ are curved outward, and the entire ornament has the appearance of a fan.

What I claim as new, and desire to secure by Letters Patent, is—

The design for a hair-ornament, composed of a series of scallops, which are united at their butt-ends and made to spread from said butt-ends to their tips in the form of a fan, with curved sides and rounded points, as shown and described.

In testimony that I claim the foregoing as my invention I have signed it this 3d day of 35 March, 1882.

JEAN R. KRAUSE.
